UNITED STATES PATENT OFFICE.

ADOLPH PETZOLD, OF PHILADELPHIA, PENNSYLVANIA, ASSIGNOR TO JOHN H. BROMLEY, JOSEPH H. BROMLEY, AND EDWARD BROMLEY.

DESIGN FOR A RUG.

SPECIFICATION forming part of Design No. 22,578, dated July 4, 1893.

Application filed June 2, 1893. Serial No. 476,399. Term of patent 3½ years.

To all whom it may concern:

Be it known that I, ADOLPH PETZOLD, a citizen of the United States, residing in the city of Philadelphia, State of Pennsylvania, have invented and produced a certain new and original Design for a Rug, of which the following is a full, clear, and exact description, reference being had to the accompanying drawing, forming a part of this specification.

My invention relates to the surface ornamentation of a rug, and consists of the design therefor shown in the accompanying drawing, in which the distinguishing features are four dogs resting couchant, forming a field center, with floral and vine-like ornamentation at each end of the rug, and extending partly over and under the field center. 15

I claim—

The design for a rug substantially as shown and set forth. 20

In testimony whereof I have hereunto affixed my signature this 27th day of May, A. D. 1893.

ADOLPH PETZOLD.
